UNITED STATES PATENT OFFICE.

JOHN A. MEYERS, OF FORESTELL, MISSOURI.

STOVEPIPE-JOINT LOCK.

1,217,805.

Specification of Letters Patent. Patented Feb. 27, 1917.

Application filed April 12, 1916. Serial No. 90,625.

To all whom it may concern:

Be it known that I, JOHN A. MEYERS, a citizen of the United States, residing at Forestell, in the county of St. Charles and 5 State of Missouri, have invented certain new and useful Improvements in Stovepipe-Joint Locks; and I do hereby declare the following to be a full, clear, and exact description of the invention, such as will enable others skilled in the art to which it 10 pertains to make and use the same.

This invention relates to new and useful improvements in a stove pipe joint lock and one of its objects is the provision of a device of this character, which shall be simple, durable and efficient, and which may be manufactured and sold at a comparatively low cost.

Another object of this invention is to provide oppositely disposed lugs upon the interior of one section of the stove pipe and adapted to be received in locking grooves formed in the other section and said grooves being so constructed that the lugs will be 25 held against accidental withdrawal, preventing the sections of the stove pipe from parting.

A further object of this invention is to provide the grooves with a downwardly inclined branch, to cause the sections to be drawn in the direction of each other, when one section is rotated causing the lugs to travel in the inclined branches of the grooves, thus drawing the sections together.

35 With these and other objects in view as will become more apparent as the description proceeds, the invention consists in certain novel features of construction, combination and arrangement of parts as will 40 be hereinafter more fully described and claimed.

For a complete understanding of my invention, reference is to be had to the following description and accompanying drawing, 45 in which:—

Figure 1 is a side elevation of a stove pipe joint lock, constructed in accordance with my invention,

Fig. 2 is a longitudinal sectional view, 50 taken on the line 2—2 of Fig. 1, illustrating the lugs held within the grooves against accidental displacement, and

Fig. 3 is a fragmentary vertical sectional view taken on the line 3—3 of Fig. 1.

Referring in detail to the drawing, the 55 numerals 1 and 2 indicate the sections of a stovepipe. Each of the sections are provided with oppositely disposed squared lugs 3 upon the interior and adjacent one end thereof. The lugs are formed by stamping 60 them out from the sections with any suitable blunt instrument.

The other end of the sections 1 and 2 is provided with grooves consisting of relatively off set inner and outer vertical 65 branches 4 and 5 and an inclined branch 6 extending downwardly from the lower end of the outer branch 4 to the upper end of the inner branch 5 and a horizontal locking branch 7 extending from the lower end of 70 the inner branch 5 in the direction of the lower end of the outer branch 4. The locking branch 7 is provided within its inner wall with an off set portion to form a socket 8 for receiving and holding the lug 3 when 75 the sections 1 and 2 are in a locked position.

In locking the sections 1 and 2 together, the lugs 3 are pushed downwardly in the vertical outer branches 4 and rotating the section 2 on the section 1, in one direction, 80 the lugs will travel in the inclined branches 6, drawing the section 2 on the section 1. The section 2 is then pushed downwardly and the lugs traveling in the inner vertical branches 5 and rotating the section 2 in an 85 opposite direction from the first direction of rotation, the lugs will travel in the locking branches 7 into the sockets 8 and be held against accidental withdrawal.

While I have shown and described the 90 preferred embodiment of my invention, it will be understood that minor changes in construction, combination and arrangement of parts may be made without departing from the spirit and scope of the invention 95 as claimed.

Having thus described my invention, what I claim is:—

In a device of the character described consisting of telescopic stove pipe sections, 100 a pair of lugs formed on one end of each of said sections, the other end of said sections being provided with oppositely disposed locking grooves, each of said grooves consisting of relatively off set inner and outer vertical branches, and an inclined branch 105 extending downwardly from the lower end of the outer branch to the upper end of the

inner branch and a horizontal locking branch extending from the lower end of the inner branch in the direction of the outer branch and provided with a socket in
5 the bottom wall thereof to hold the lugs against accidental withdrawal.

In testimony whereof I affix my signature in presence of two witnesses.

JOHN A. MEYERS.

Witnesses:

GEO. N. RIEMEIER,
G. C. FRIDLEY.
